UNITED STATES PATENT OFFICE.

ERNEST C. WILCOX, OF MERIDEN, CONNECTICUT, ASSIGNEE TO THE CONNECTICUT TELEPHONE & ELECTRIC COMPANY, OF MERIDEN, CONNECTICUT, A CORPORATION OF CONNECTICUT.

IGNITER MECHANISM.

1,182,867.

Specification of Letters Patent.

Patented May 9, 1916.

Original application filed June 18, 1914, Serial No. 845,834. Divided and this application filed December 4, 1914. Serial No. 875,413.

To all whom it may concern:

Be it known that I, ERNEST C. WILCOX, a citizen of the United States, residing at Meriden, county of New Haven, State of Connecticut, have invented certain new and useful Improvements in Igniter Mechanism, of which the following is a full, clear, and exact description.

My invention relates to an improved apparatus for electrical ignition systems, the object being to so construct such devices as to make them exceedingly compact and reliable, and so as to likewise make the various parts easily accessible for cleaning, repair, and placement.

This is a division from my co-pending application Serial Number 845,834, filed June 18th, 1914.

In the accompanying drawings, Figure 1 is a vertical sectional view showing certain parts in elevation. Fig. 2 is a plan view with certain parts removed. Fig. 3 is a plan view with other parts removed.

1 represents a rotatable shaft. 2—2 are cams thereon.

3 is a housing having a central passage for the shaft 1.

4 is a condenser located in the lower part of the housing 3 and preferably removable.

5 is a removable cover plate, while 6 represents a spring locking ring seated in a groove in the inner wall of the chamber in which the condenser is located, whereby the plate 5 may be held in place. In the particular form shown, the lower part of the housing or chamber in which the condenser is located is separated from the upper part of the housing by an intermediate partition in which may be provided two holes 7—7, whereby when it is desired to separate the parts, a suitable blunt tool may be inserted through the passages 7 to push the condenser out after the plate 5 has been removed.

45 In the upper part of the housing is the so-called timer, as set forth in my original application from which this is a division, it is preferable that this timer be mounted as a unit on a removable carrier element 8, 50 which has a central passage for the shaft 1. The cams 2—2 operate the interrupter parts. The interrupter includes the swinging breaker arm 11, carrying a contact point 10 arranged to coact with the fixed contact

point 9. The arm 11 is moved by the cam 2 55 to make and break the circuit through the points 9—10. Mounted on top of the casing is the distributor so-called, which includes the rotary contact member 24 mounted on the upper end of the shaft 1, and the terminal segments 25—25 which are mounted in a suitable housing 22. As the shaft revolves, the brush or contact 24 will encounter successively the terminal segments 25, and the breaker arm 11 will be properly actuated to 65 make and break the primary circuit, whereby the high tension circuit which passes through the distributor will be closed at the proper time. The entire apparatus is rotatable relatively to the shaft 1 in the usual 70 manner to advance or retard the spark.

20 is a removable cap for the housing 3, the housing 22 resting thereon. The parts 22 and 3 may be connected in any suitable manner as by spring clips 29 carried by 75 one part and engaging headed studs 30 carried by the other part.

In the particular form shown, the primary circuit is of the so-called grounded type instead of all metal type, although it 80 is obvious that it is immaterial which one of these two methods of circuit is employed. In the drawings shown, one end of the primary circuit is provided with the terminal or binding post 15, the inner end of which 85 is electrically connected with one of the interrupter terminal points, the said terminal 15 being insulated from the housing 3. This terminal is likewise electrically connected with the condenser 4 through the medium 90 of a brush 31, while the other side of the container is grounded by contact on the case or housing, the brush 31 being, of course, insulated from the housing.

My present divisional application relates 95 particularly to the construction and arrangement of the condenser and associated parts. So far as I am aware, I am the first to employ the condenser in this particular combination of parts associating the same in 100 direct conjunction with the timer or interrupter. Heretofore condensers have been placed at some relatively remote place, and have been electrically connected with the interrupter by correspondingly long wires, 105 which have invited induction, condenser leakage and short-circuiting by faulty installation or worn insulation. Furthermore,

by the old arrangement of such parts, I have shown that unnecessary labor has been required in making and safeguarding the connections. By my improvement shown 5 herein, the condenser is securely held within the same housing in which the interrupter mechanism is located, whereby said parts may be electrically connected by an exceedingly short connecting means, such as for 10 example the brush 31, all of which guarantees the adequate protection of the electrical connecting means and reduces to the minimum all danger of short-circuiting, induction, condenser leakage, and other 15 troubles incident to apparatus of this character, due to remote electrical connection.

What I claim is:

In an ignition apparatus of the character

described, a supporting shaft, a housing revolubly mounted thereon and supported thereby, interrupter mechanism carried within said housing and protected thereby, a condenser also carried within said housing and protected thereby, a terminal screw entered into one side of said housing and insulated therefrom, an electric connection inside the housing from said terminal screw to one part of said interrupter and a brush inside the housing connected between the terminal screw and one side of the condenser, said connections being thereby all wholly protected by said housing. 20 25 30

ERNEST C. WILCOX.
